UNITED STATES PATENT OFFICE.

FRANK E. WOLCOTT, OF HARTFORD, CONNECTICUT.

DESIGN FOR A DISH-WASHING MACHINE.

• 55,351.

Specification for Design.

Patented May 25, 1920.

Application filed January 20, 1920. Serial No. 352,866. Term of patent 7 years.

To all whom it may concern:

Be it known that I, FRANK E. WOLCOTT, a citizen of the United States, residing at Hartford, in the county of Hartford and State of Connecticut, have invented a new, original, and ornamental Design for a Dish-Washing Machine, of which the following is the specification, reference being had to

the accompanying drawing, forming part thereof.

The figure is a perspective view of a washing machine showing my new design.

I claim:

The ornamental design for a dish washing machine as shown.

FRANK E. WOLCOTT.
